LADDER HOIST

William G. Kuehn and Monte E. Hover, Culver City, Calif., assignors of one-third to Fred Jervis and one-third to J. B. Miller, both of Los Angeles, Calif., and one-third to Monte E. Hover, Culver City, Calif., jointly

Application September 16, 1938, Serial No. 230,276

10 Claims. (Cl. 228—12)

Our invention relates generally to hoists and particularly to a hoist which may be removably mounted on a truck or other vehicle for use by fire departments, street decorators, power and traction companies, and the like where a portable telescopic ladder is needed.

It is the major object of our invention to provide a hoist which is particularly suitable for the above uses, and which is also adaptable to other uses, such for example as operating the bed of a dump truck, or the like, and which can be easily installed on any suitable vehicle and just as easily removed when necessary.

It is a further object of our invention to provide a hoist which is easily accessible, and because of its simplicity and durability will give long and satisfactory service.

These and other objects and advantages of our invention will become apparent from the following description of a preferred embodiment thereof as a ladder hoist, and from an inspection of the accompanying drawings, in which:

Fig. 1 is a side elevation of a conventional fire truck equipped with our invention,

Fig. 2 is a side elevation of the ladder hoist in retracted or normal position,

Fig. 3 is a plan view of the hoist in normal position,

Fig. 4 is an elevational section taken on the line 4—4 in Fig. 3,

Fig. 5 is an elevational section taken on the line 5—5 of Fig. 3,

Fig. 6 is a partial elevation showing the hoist in raised position,

Fig. 7 is a partial elevational section taken at 7—7 in Fig. 3, and

Fig. 8 is a fragmentary vertical section taken at 8—8 in Fig. 3.

Referring now to the drawings, and particularly to Figs. 1—3 thereof, the numeral 10 indicates generally a suitable vehicle which in the drawings has been illustrated as a fire truck, and the numeral 11 indicates generally the ladder hoist of our invention, mounted on the rear end 45 of the truck 10 by a suitable framework such as the posts 12 and diagonal braces 13. As seen best in Figs. 2 and 4, the hoist is mounted on a relatively flat table 14 which, in the preferred form of our invention, is rotatably mounted upon a base plate 15 supported by a box frame 16 made of horizontal channels.

The box frame 16 is provided with a pair of parallel channels 17 and 17a adjacent its center section, across the bottom of which a plate 18 is bolted. A relatively large gear wheel 19, pro-

vided with a hub 20 and spokes 21, is secured to the upper faces of the channels 17 and 17a so that its hub is substantially co-axial with the center of frame 16 and table 14 as seen best in Fig. 4. The base plate 15 is provided with a central aperture which is preferably circular in shape and of somewhat greater diameter than the gear wheel 19. The table 14 is provided with a centrally-disposed relatively small aperture, over which is bolted an apertured bearing plate 22. 10 A vertical shaft 23 is secured in the hub 20 of gear 19 with its lower end passing through an aperture in plate 18 and secured thereto as by nut 24. The upper end of the shaft passes up through the aperture in base plate 15 and through 15 a small aperture in table 14 and an apertured bearing plate or boss 22, so that the table may be rotated about shaft 23. The table is prevented from moving vertically by any suitable means such as the nut 25 on the top of shaft 23. 20

A pair of parallel channel irons 26 and 27 are securely fastened to the upper face of table 14, and are spaced apart a distance substantially equal to the width of the ladder which the hoist is to carry. A gear box 28 provided with a boss 29 25 on its inside wall is preferably mounted adjacent one edge of the table 14, and houses beveled gears 30 and 31 carried by shafts 32 and 33, respectively. Shaft 32 is vertically disposed within the gear box 28, extends upwardly through the top 30 thereof, and has a handwheel 34 secured to its upper end. Shaft 33 extends horizontally through the boss 29 and a bearing aperture in channel 26 and carries a beveled gear 35 on its inner end which meshes with a gear 36 carried on the upper end of a vertical shaft 37 rotatably mounted in table 14 and extending down through the enlarged aperture in plate 15. A gear 38 is fast to the lower end of shaft 37, and is adapted to mesh with gear wheel 19. By this 40 arrangement, table 14 may be readily rotated in a horizontal plane about the base plate 15 by simply turning the handwheel 34 whose motion is transmitted through shaft 32, gears 30 and 31, shaft 33, gears 35 and 36, shaft 37, and gears 38 and 19 to gear 38 to cause it to travel around gear 19.

The table 14 carries suitable ladder supporting means pivotally mounted thereon such for example as the pair of parallel legs 41 and 42 50 which are adapted to have a ladder 40 securely attached thereto in such manner that the legs 41 and 42 act as lower extensions of the ladder legs, and are pivotally mounted on the anchor bars 26 and 27 adjacent one end thereof by 55

means of upstanding ears 43 and 44 through which an axial rod 45 extends, the rod 45 being secured in place by means of nuts 46 and 47. The legs of the ladder 40 may be secured to the 5 hoist legs 41 and 42 by any convenient means, such as bolts 48, and as seen best in Fig. 2, the hoist legs 41 and 42 with their associated ladder 40 are adapted to normally rest in a substantially horizontal position, so that the supporting vehicle 10 may be readily moved from place to place without interference.

A shaft 49 is journaled in the hoist legs 41 and 42 and carries gears 50 and 51 adjacent its opposite ends outside of the legs 41 and 42 15 whose function will be discussed later.

A pair of parallel horizontally-disposed slides 52 and 52a rest on the table 14 and are slideable thereacross, being held in position by a plurality of upstanding guides 53 and 53a, 54 and 54a, 20 respectively, said guides being provided with rollers 55 which bear upon the top face of the slides 52 and 52a to hold them in position on the table 14. The guides are preferably formed of pairs of opposed upstanding L-shaped sections, so as 25 to prevent lateral movement of the slides. The slides 52 and 52a are each provided with a notch 56 in their upper face adjacent one end thereof. The guides 53 and 53a are provided with dogs 57 carried by the channels 26 and 27, which are 30 adapted to normally bear against the upper face of the slides 52 and 52a and to engage the notches 56 when the slides are in normal position as shown in Figs. 2 and 5. Pivotedly attached to the other end of slide 52 is a rack 60 and a similar 35 rack 60a pivotedly connected to the rear end of slide 52a. The racks 60 and 60a are disposed, so that they rest on and engage gears 50 and 51 respectively, and are held in engagement against their respective gears 50 and 51 by pairs of straps 40 61 and 61a and 62 and 62a pivotally mounted on the shaft 49 and extending therefrom on either side of their respective racks. The outer ends of the straps 61 and 61a and 62 and 62a are connected by short shafts upon which are rotatably mounted a pair of rollers 63 and 64 and 45 63a and 64a, respectively, which rollers bear against the upper face of the racks 60 and 60a.

One end of the shaft 49, in the drawings the 50 end which extends through the hoist leg 41, is provided with a gear 65 adapted to mesh with a smaller gear 66 carried on a short shaft 67 which extends between leg 41 and a wall 68. Shaft 67 55 extends through the wall 68 and carries a large gear 69 on its outer end, which in turn meshes with a small gear 70 carried on a shaft journaled in wall 68 and the outside wall 71 of the gear box, the shaft of gear 70 carrying a handwheel 72 on its outer end outside of the gear box, said 60 gears forming a reduction gear train, whereby rotation of the handwheel 72 rotates the shaft 49 with its associated gears 50 and 51.

A locking block 73 is mounted on the wall 74 65 of said gear box and is apertured and disposed so that it surrounds the shaft 67. The block 73 is slit below the aperture which contains the shaft 67 and a bolt 75 extends through the block 73 and wall 74 and is connected to an eccentric lever 76, so that movement of the lever causes the bolt 75 to compress the two sections of the 70 block 73 about the shaft 67 to lock it against rotation.

A shaft 80 is journaled between the anchor plates 26 and 27 and is provided at each end with dogs 81 and 81a which are pressed downwardly by spring 82 surrounding the shaft 80, 75

and are adapted to engage the notches 56 in the slides 52 and 52a when they travel to their lefthand position, as shown in dotted lines in Fig. 5, and full lines in Fig. 6. The shaft 80 is provided with a handle 83 by means of which 5 the shaft 80 can be rotated against the action of the spring 82 to disengage the dogs 81 and 81a from their respective notches in the slides 52 and 52a.

In the interest of safety and efficiency, we 10 prefer to provide all of the gears with covers or housings as shown in the drawings, it being thought unnecessary to specifically mention each covering by name and number.

In the normal position of our apparatus as 15 shown in Figs. 1 and 2, the legs 41 and 42 are substantially horizontal and the slides 52 and 52a are in their righthand position, the racks 60 and 60a being slightly inclined and engaging the gears 50 and 51 as illustrated. To raise the 20 ladder 40 and position it for use, the locking block 73 is released and the hand wheel 72 is rotated in a counter-clockwise direction, which rotation by reason of the gear train connected thereto rotates the shaft 49 and its gears 50 and 25 51 in a counter-clockwise manner. This rotation of the gears 50 and 51 which are in engagement with the racks 60 and 60a causes the racks to rotate clockwise about their pivotal mountings on slides 52 and 52a, and also causes said slides 30 to move to the left in the guides 53 and 54 until the arms 60 and 60a are in upright position (as seen in Fig. 5) and the notches 56 on the slides 52 and 52a have been engaged by the dogs 81 and 81a on the left side of the table 14. The 35 handwheel 72 is then rotated in the opposite direction, in this case clockwise, and since the slides 52 and 52a are locked by the dogs 81 and 81a against movement to the right, gears 50 and 51 are caused to travel up the racks 60 and 60a, causing both the legs 41 and 42 and the racks 40 to rotate in a counter-clockwise direction to a position, such as shown in Fig. 6. It will be apparent that continued rotation of the handwheel 72 will cause the gears 50 and 51 to travel out to the end of their respective racks 60 and 60a 45 and the length of said racks is such that when the gears reach the ends of their respective racks, the hoist legs 41 and 42 are substantially vertical. It will be understood of course that the legs 50 41 and 42 can be stopped in any desired position between the horizontal and the vertical, and while normally there is sufficient braking effect by reason of the reduction gears, as a matter of caution the braking block 73 is clamped around the shaft 67 by moving the lever 76, so that 55 further movement of the gears and shaft in either direction is prevented.

When the ladder has been erected, it can be 60 positioned by rotating the table 14 to any point desired by simply operating the handwheel 34 through its gear train as previously described. It will be understood of course, that if desired, the rotational position of the table 14 can be adjusted prior to the erection of the ladder.

When it is desired to lower the ladder, the 65 brake block 73 is released, the handwheel 72 is rotated in a counter-clockwise direction until the ladder has resumed its horizontal position, and the traveling racks are in a substantially vertical position as shown in dotted lines in Fig. 5. The handle 83 is then moved in a counter-clockwise direction to disengage the dogs 81 and 81a from their respective notches in slides 52 and 52a and the handwheel 72 is rotated in a 70 clockwise direction to cause the racks 60 and 60a 75

to travel along the gears 50 and 51 until they are in their retracted position, and the slides 52 and 52a have moved to the right end of their travel, at which point the dogs 57 and 57a engage the notches 56 and prevent further movement of the slides and said racks.

While we have shown our preferred form of hoist as including means for moving the racks from retracted position to upright position, it is to be understood that we also mean to include in our invention a hoist in which the racks are pivoted directly on the table with no means being provided for retracting them, in which case they would normally be in an upright position. From the foregoing, it will be seen that we have provided a very simple and durable hoisting device by means of which one man can raise, lower, and adjust a large ladder or other apparatus which otherwise would be impossible for him to handle. While we have illustrated a preferred embodiment of our invention as applied to ladders, it is to be understood that our hoist can be used for many other purposes, and that the use of the word "ladder" herein is for convenient illustration and is meant to include other apparatus with which our invention can be successfully associated.

We claim as our invention:

1. A ladder hoist of the character described which includes: a table; ladder-supporting means pivotally mounted on said table; gear means carried by said ladder-supporting means; a horizontal slide mounted on said table; a rack pivotally mounted on said slide and engaging said gear means; and means for rotating said gear means to thereby rotate said ladder-supporting means about its supporting point on said table.

2. A ladder hoist of the character described which includes: a substantially horizontal table; a ladder support pivotally mounted at one end on said table; a transverse shaft journaled in said support and carrying gear means; a horizontal slide mounted on said table; guides on said table for restricting the movement of said slide; a rack pivotally connected at one end to said slide; means carried by said support for holding said rack in engagement with said gear means; means for rotating said gear means to cause it to travel along said rack; and means for locking said slide in the position it assumes when said rack is in an upright position, whereby rotation of said gear means in one direction moves said slide into locked position and raises said rack and subsequent rotation of said gear means in the opposite direction raises said ladder support.

3. A ladder hoist of the character described which includes: a substantially horizontal table; a pair of ladder supporting legs pivotally mounted at one end on said table; a pair of horizontal slides on said table with guides for restricting their movement; a rack pivotally mounted on each of said slides; a transverse shaft journaled in said legs carrying a gear adjacent each end thereof adapted to engage said racks; means for holding said racks in engagement with their respective gears; a reduction gear train associated with said gear shaft; and means for locking said slides in the position they assume when said racks reach an upright position by reason of rotation of said gears in one direction, whereby rotation thereof in the opposite direction causes them to ride up said racks thereby raising said legs about their pivotal mountings.

4. A ladder hoist as defined in claim 3 in which one of the gears of said train is mounted

on a shaft which has an apertured block associated therewith adapted to lock said shaft and thereby said legs in any desired position.

5. A ladder hoist as defined in claim 3 in which said slide locking means comprises spring pressed dogs carried on said table.

6. A ladder hoist as defined in claim 3 in which the means for holding the rack in engagement with the gear comprises strap means mounted on the gear shaft and extending outwardly beyond said rack, and provided with a pair of rollers which ride on the upper face of said rack.

7. A ladder hoist of the character described which includes: a table; ladder-supporting means pivotally mounted on said table; gear means carried by said ladder-supporting means; a horizontal slide mounted on said table; guides on said table for restricting the movement of said slide; a rack pivotally mounted on said slide and engaging said gear means; means for rotating said gear means; and means for locking said slide in the position it assumes when said rack is in an upright position, whereby rotation of said gear means in one direction moves said slide into locked position and raises said rack and subsequent rotation of said gear means in the opposite direction raises said ladder support.

8. A ladder hoist of the character described which includes: a substantially horizontal table; a ladder-support pivotally mounted at one end on said table; a transverse shaft journaled in said support and carrying gear means; a horizontal slide mounted on said table; a rack pivotally connected at one end to said slide; means carried by said support for holding said rack in engagement with said gear means; and means for rotating said gear means to cause it to travel along said rack and thereby rotate said ladder-support about its pivotal mounting.

9. A ladder hoist of the character described which includes: a table; ladder-supporting means pivotally mounted on said table; gear means carried by said ladder-supporting means; a rack pivotally mounted on said table and slidable thereon, and engaging said gear means; means for rotating said gear means to thereby rotate said ladder-supporting means about its supporting point on said table; and locking means cooperating with said rack, whereby rotation of said gear means while said locking means is disengaged causes rotation of said rack, and rotation of said gear means in the opposite direction when said locking means is engaged causes rotation of said ladder-supporting means.

10. A ladder hoist of the character described which includes: a substantially horizontal table; a ladder support pivotally mounted at one end on said table; a transverse shaft journaled in said support and carrying gear means; a rack pivotally connected at one end to said table and slidable thereon; means carried by said support for holding said rack in engagement with said gear means; means for rotating said gear means to cause it to travel along said rack and thereby rotate said ladder support about its pivotal mounting; and locking means cooperating with said rack, whereby rotation of said gear means while said locking means is disengaged causes rotation of said rack, and rotation of said gear means in the opposite direction when said locking means is engaged causes rotation of said ladder-supporting means.
